AIR CONDITIONING SYSTEM

Edward Kent, Highland Park, Mich.

Application May 8, 1939, Serial No. 272,362

8 Claims. (Cl. 237—51)

This invention relates to air conditioning systems for buildings and is a continuation in part, in respect to common subject matter, of my United States application, Serial No. 199,383, filed April 1, 1938. The system is especially adapted for use in dwellings, the purpose being to provide a new and improved mechanism and manner of operation whereby the interior of the building may be maintained at a temperature below or above the exterior atmospheric temperature and thus maintain the building cool or warm as may be desired.

A feature and object of the invention is to provide in association with a gas, electric or oil heating member, preferably in the form of a fireplace, for taking air from atmosphere in such relation to the heating element that it may be discharged into the building either heated or cooled. In view of air being forced into the room or interior of the building thus tending to produce pressure therein or an accumulation of gas fumes if a gas or oil fired heating element be provided, a point of egress for air is provided to thus maintain the room or interior of a building at or near atmospheric pressure and by use of a fan provide for complete change of air in a room over a period of time and preventing a detrimental accumulation of fumes therein.

It is also an object and feature of the invention to provide a gas grate having open flame providing a flow of heated air and discharging fresh air into the said heated air to mix therewith as it is discharged into the room.

A further object and feature of the invention resides in the provision of a gas grate as hereinafter more fully described having a sheet metal back heated by the gas burner and providing a passageway on the opposite side of the sheet metal back and discharging fresh air through the passageway to absorb heat from the said sheet metal back and discharging the air into the room in mixture with the heated air developed by the gas burner.

It is further a feature and object of the invention to provide in association with a gas or electric grate to position in the air passageway at the back of the grate a means for chilling the air and thus provide a structure that is adapted to discharge heated or cooled air from atmosphere into the room.

A further object and feature of the invention resides in the provision of a pair of gas fired grates in a partition wall arranged with the backs of the grates in spaced relation with the face of each grate toward the respective room on opposite

10 sides of the partition providing an air passageway therebetween and a blower associated therewith for discharging air from atmosphere into the passageway, there being at the top of the grates a passageway opening directly to the respective rooms through which air from the passageway between the grates is discharged and with which the heated air on the face of the grates is mixed with the air blowing into the room.

15 A further object and feature of the invention is in the provision of a gas burning grate or fireplace having a gas burner on the front of the grate and a transparent closure for the front of the grate formed of a convenient material such as a fire resistant glass, and a passageway for air to enter the enclosure at the bottom and a passageway at the top for the heated air and a passageway for air from atmosphere discharging jointly with the heated air into the room through an aperture preferably provided with a grating or grille whereby the air from atmosphere is mixed with the heated air provided by the gas burner prior to discharge into the room.

20 25 A major object of the invention is to provide in a composite structure a heating and a cooling element and in association therewith means for providing air under pressure to be heated or cooled at will and discharged to the area requiring corresponding temperature change.

30 35 These and other features and objects of the invention are hereinafter more fully described and claimed and the preferred form of apparatus embodying my invention is shown in the accompanying drawings in which—

35 Fig. 1 is a diagrammatic plan view showing one arrangement of the various conduits and the dual heating and cooling elements associated therewith.

40 Fig. 2 is a vertical section showing a building and the associated heating and cooling elements and control means therefor.

45 Fig. 3 is an enlarged vertical section of the heating and cooling elements taken on line 3—3 of Fig. 1.

Fig. 4 is a front elevation of the heating unit partly broken away to show the gas heating element.

Fig. 5 is a detail of a gas control valve partially in section taken on line 5—5 of Fig. 4.

50 Fig. 6 is an enlarged vertical section showing a portion of an air outlet for the interior of the building taken on line 6—6 of Fig. 1.

Fig. 7 is a vertical section of the assembled heating and cooling units when used without a continuation conduit to the ceiling of a room

particularly adapted for installation in existing structures.

Fig. 8 is a front elevation of the unit shown in Fig. 7 partially broken away to show the interior construction.

Fig. 9 is an elevation of a portion of the air inlet conduit where basement area is provided.

Fig. 10 is an elevation of the arrangement of a portion of the intake conduit where no basement is provided.

The principal feature of this invention resides in a combined heating and cooling apparatus whereby a tempered air above or below atmospheric temperature may be provided by discharging a stream of air from atmosphere through the associated heating and cooling structure to discharge directly into a room and this form of the apparatus is first described due to it being desirable that this feature of the system should be first well understood in order that the description of the system as a whole may be readily realized.

The preferred element for producing heat is a gas grate one form of which is shown at 1 in Fig. 3 for use in a room at the right hand side of the partition wall 2 and a similar gas grate 3 is formed in the same body casting 4 with the back wall 5 of the grate 1 being opposed to the similar back wall 6 of the grate 3. These back walls are spaced to provide a passageway 7 therebetween and the main casting 4 is here shown as having peripheral channels 8 and 9 on opposite sides of the passageway 7. These channels 8 and 9 extend peripherally about the casting, as will be understood from Fig. 4, and water may be introduced into these passageways through an opening not here shown and each channel is provided with an outlet valve 10 of a character to open on pressure in the passageways 8 and 9 to provide steam to be injected into the air stream. A hood 8^a and 9^a is provided in the arrangement here shown to house the valves 10.

The gas grates 1 and 3 may be of any approved form but are here shown as having burners 11 of hollow form to which gas may be provided by a respective conduit 12 or 13 and with each of which is provided a control valve 14 and 15 respectively. The burner tubes 11 have apertures directing the flame 16 against a back plate of the grate member at the bottom. Thus the burning gases will impinge upon the back plate and will rise to pass into a channel 17 or 18 for the respective grates. Air is provided for the burner through apertures 11^a and 11^b in a casing 11^c enclosing the burner tube for each grate.

These channels 17 and 18 open at the upper end to a respective outlet conduit 19 or 20 so that air passing through the conduit 7 passes into either or both the open ends of the passageways 17 and 18. The air outlet passageways 19 and 20 are closely arranged at the rear of the grille 21 or 22 for the respective grates and the air and gases in combustion pass through the grilles into the respective room. Air is forced under pressure into the passageway 7 by a conduit 23 which, as is hereinafter described, takes air from atmosphere. Thus fresh air in association with the gases in combustion is discharged through the grille under these conditions and the said air stream is partially heated by contact with the faces of the back walls 5 and 6 of the grates prior to discharge into the room in mixture with the gases in combustion.

Preferably, although not necessarily, a transparent shield 24 for the grate 1 and 25 for the grate 3 may close the face of the grates in the

respective room and the members 24 and 25 are preferably formed of a heat resistant glass. By this arrangement all of the heated gases are discharged upwardly and into the fresh air stream passing through the outlets 19 and 20 from the passageway 7.

In the construction shown in Fig. 3 the partition wall above the grates is constructed to form a passageway 7' in continuation of the passageway 7 and at the upper end of the passageway 7' is a shield 26 shaped to form a deflector member for causing air to pass to the right and to the left through grilles 27 and 28 into the respective room on the right and left side of the partition. Thus the heated air can be discharged directly to the upper part of the room if desired and it is also to be noted that on the inner sides of the grilles 27 and 28 are damper elements 29 and 30 respectively which may be operated in any convenient manner to open and to close the same to permit or prevent flow of air through either or both the grilles 27 and 28. Likewise there is a damper element 31 for the air conduit 19 and a similar damper element 32 for the air conduit 20. These last named damper elements may be controlled by a lever 33 for the grille 21 and by a similar control element for the grille 22 such control lever being shown clearly in Fig. 4.

Preferably the opposed inner faces of the back plates 5 and 6 have a backing 34 of silica sand held in place by the shield 35 in each instance, the shields being supported at the lower end by a casting 36 formed integral with the back plate. These members 34 and 35 are spaced apart and between the same is a cooling coil 37 of a refrigerating apparatus (not here shown) but to be understood as being connected with the circulating system of the refrigerating apparatus by a conduit 38.

Preferably this coil is the expansion coil of a condenser-compressor-expander type of artificial refrigerating apparatus although other types of cooling apparatus may be utilized if desired. Such coil is to be used when it is desired to cool the air flowing between the two plates to lower the temperature of the air in the room in respect to atmospheric temperature and when in use the gas burners are shut off by the valves 14 and 15.

It is also to be understood that the channel 7' and the upper grilles 27 and 28 and associated parts may be dispensed with in which case the heating and cooling unit will remain substantially the same as described in respect to Fig. 3 and thus the elements 34 are not described in respect to Fig. 7. The structure of Fig. 7 differs from that shown in Fig. 3 in the fact that no water channels 8 or 9 are provided as the heating and cooling element is usable without the provision of means for injecting steam into the air stream as is provided for in the structure shown in Fig. 3. In Fig. 7 the air passageway 7^a (which corresponds to the passageway 7 of Fig. 3) terminates at the top wall 39 and the air flow through the passageway 7' from the air conduit 23 is directed through the grilles 40 and 41 and the associated damper elements. The character of structure shown in Fig. 7 is used where there is no requirement for the channel 7' of Fig. 3 or in a single story room where there is no necessity for discharging heated or cooled air above the grates, as for instance to an upper room, as would be possible with the structure shown in Fig. 3 in which case the grilles 27 and 28 would be located adjacent the floor of an upper room

such floor being indicated by dotted lines *a*—*b* of Fig. 3.

In Fig. 1 is shown a typical layout of the air conduits and grate elements, it being understood that these conduits will of necessity change in position depending upon the arrangement of rooms of the building and the location of the grate elements.

The preferred means for providing air for the grate elements is shown in detail in Fig. 2 which consists of a conduit 23 preferably positioned beneath the floor 42 and discharging to the grate elements as described relative to Fig. 3. The intake end of this conduit 23 is provided by a vertical conduit 43, the upper end of which is provided with a chambered element 44 having a front face formed with louvres 45 for ingress of air from atmosphere. The horizontal portion of the conduit 23, in the arrangement shown in Fig. 2, is provided with a chamber 46 to which the vertical conduit 43 opens on one side and to which the conduit 23 opens on the other side. There is a fan in the chamber 46 of any approved type shown at 47 and in the base of the chamber is provided a quantity of water 48 in which the condenser coil 49 of a refrigerating system may be located. The water may be supplied through a conduit 50 having a valve controlled by a float 51. When the water is depleted below a certain level the valve opens and water is sprayed into the chamber 46 through the spray heads 52 so positioned that air passing into the conduit 23 must first pass through the spray. Such arrangement provides for introduction of moisture in the air stream and may be utilized rather than the arrangement described in Fig. 3 having the water conduits 8 and 9.

Whether or not water spraying means is used in the chamber 46 I preferably provide air filters 53 in the conduit 23 or in the branches thereof as indicated at 23^a and 23^b in Fig. 1. Considering Fig. 1 the dotted lines 55 indicate the outer wall of a building while the dotted lines 56, 57, 58, 59 and 60 show partition walls. The conduits 23^a and 23^b discharge to the grate element 61 or 62 respectively positioned in the partitions 60 and 56. The cooling and heating unit 62 is arranged to discharge cooled or heated air to the rooms A and B on opposite sides of the partition wall 56 and there is an extension conduit 23^c in continuation of the conduit 23^b which, as shown in Fig. 2, has a vertical portion 23^d providing a discharge outlet at the upper end adjacent the ceiling. The conduit 23^c is controlled by the damper 23^e operable in any approved way to permit or prevent flow of air from atmosphere to the room ceiling. The conduit 23^b is likewise controlled by a damper 23^f and other dampers may be provided in the conduits to control flow of air therethrough. In any case the air must first pass through the filters 53 before discharging to the heating and cooling units or into the room. The heating and cooling grate element 63 is supplied with air through the conduit 23.

In view of the fact that air is discharged into the interior of the building through the heating and cooling unit it is desirable, especially when the heating units are in operation, to withdraw air from the room to maintain a substantially pure air therein and without accumulation of pressure. For this purpose I provide a main conduit 65 having an opening to atmosphere as at 66 and in the room adjacent the opening is provided a fan 67. The main conduit 65 is connected as by branches 68 and 69 with a grilled

opening 70 and 71 respectively providing an inlet to the conduit 68.

The main air exhaust conduit 65 has a branch conduit 68 connected with the grilled opening 70 in a partition wall 59 which opens to rooms on the respective opposite sides of the wall and may be at a considerable distance from the heating and cooling device 61. The branch conduit 69 is connected with the grilled openings in the partition 56 opening on opposite sides of the partition wall to the rooms A and B. By this arrangement of conduits (which will vary in accordance with the structure and arrangement of rooms) heated or cooled air may be discharged into the rooms and by the fan 67 in the exhaust conduit 65 air is removed from the rooms to prevent an accumulation of air pressure therein and further to insure a constant change in the atmosphere in the rooms. This constant change of atmosphere is desirable whether or not the heating element be used and of course it is particularly desirable when a gas flame be used to thereby prevent accumulation of fumes in the room.

The housing for the fan 47 and means associated therewith for introducing moisture into the air stream may be located as shown in Figs. 2 or 9 where a basement room is provided. In installations where no basement is provided in either old or new structures, the said housing and moisture providing apparatus may be positioned in a room C provided therefore as shown at 75 in Fig. 10, the intake conduit being indicated at 76 and the discharge conduit at 77. The apparatus functioning exactly as described relative to Fig. 2. In old structures having a basement, the air intake 90 may be placed on the exterior of the building wall as shown in Fig. 9.

In Fig. 6 is shown the exhaust conduit 65 as having a single grilled opening 78 rather than the double grille opening 61 or 71 of Fig. 1 as such single opening may be desirable in some arrangements of the exhaust air conduits. Also, whether the exhaust openings are single or double, a damper 79 may be provided to secure a regulation of the flow of air from the room or rooms.

In the use of gas fired grates it is desirable to provide a control valve as is indicated in Fig. 5, the valve proper being housed in a casing 80 to which the gas tube 18 of Fig. 3 is connected. The valve has a shaft 81 and the hand wheel has a hub slidable longitudinally on the shaft and also rotatable on the shaft in the position shown in Fig. 5.

Thus when the valve is closed or open there will be no possibility of accidentally turning the valve by rotation of the wheel. In order to rotate the shaft 81 the wheel must be moved from the position shown to engage the lug 82 thereon in the notch 83 of a collar 84 pinned to the shaft whereupon rotation of the wheel will rotate the shaft. A coiled spring 84 is provided between the hub of the wheel and the collar tending to maintain the same in the disengaged relation shown in Fig. 5. While such valve control arrangement is desirable the invention herein disclosed and claimed is not confined to its use.

From the foregoing description it is believed evident that the various objects and features of the invention are attained by the construction described. It is further evident that with my improved air conditioning apparatus there is no necessity for chimney or chimneys nor of furnaces at a central point from which heat is distributed

by a conduit to various rooms as is commonly the case. In such prior furnace construction, especially hot air furnaces, there is a considerable heat loss while the air is traversing the conduits. By my invention the heat is developed and supplied to the air stream at its point of entrance to the room whereby my improved heating system is economical in use and by use of the dampers such as 19 and 20 of Fig. 1 the volume of air discharged to any particular room per unit of time may be varied. And likewise the first cost of the system is below that of the usual furnace system.

Further my improved air conditioning apparatus provides for removal of dust from the rooms, it being obvious that by closing the air outlets to the exhaust duct in all the rooms but one a rapid flow of air may be caused and fresh air drawn thereinto through the grilles 21, 27 or 28 and this may be accomplished even though the heating and cooling apparatus is not used.

Having thus fully described my invention, its utility and mode of operation, what I claim and desire to secure by Letters Patent of the United States is:

1. Air conditioning means for a room of a building comprising a gas burning grate having a back wall, means for supplying gases and air for combustion to the forward surface of said wall, a duct at the upper end of the grate having an opening to the room and through which the gases of combustion pass, an air conduit, one wall of which is formed by the said back wall of the grate and having an opening above the grate adjacent the duct opening, means for supplying air from atmosphere to the said air conduit, the duct being so arranged that the heated gases of combustion discharge into the stream of air from said air conduit at the top of the grate, and a grilles opening at the top of the grate through which the commingled air from atmosphere and gases of combustion pass into the room.

2. Air conditioning means for a room of a building comprising a gas burning grate having a back wall, means for supplying gases and air for combustion to the forward surface of said wall, a duct at the upper end of the grate through which the gases of combustion pass, an air conduit, one wall of which is formed by the said back wall of the grate and having an opening above the grate to which the first named duct opens, means for supplying air from atmosphere to the said passageway, the duct being so arranged that the heated gases of combustion discharge into the air stream at the top of the grate, and a grilles opening at the top of the grate through which the commingled air and gases of combustion pass into the room, and means for injecting steam into the stream of air and gases of combustion prior to discharge into the room.

3. Air conditioning means for the room of a building comprising a gas burning grate, means for supplying a gas flame to the front surface of the grate facing the room interior, a transparent shield for said front face of the grate for closing the same to the room, there being an opening at the bottom of the grate for supply of air for combustion, an air conduit at the back of the grate whereby air passing therethrough is subject to influence of the heat of the said back wall of the grate, means for discharging air through the said passageway, said passageway having an opening at the top of the grate through which the air is discharged to the room, the upper end of the said backing member being shaped to cause gases of

combustion to discharge into the air stream to temper the same prior to discharge into the room, and means for varying the volume of tempered air discharged into a room per unit of time.

4. Air conditioning means for the room of a building comprising a gas burning grate, means for supplying a gas flame to the front surface of the grate facing the room interior, a transparent shield for said front face of the grate for closing the same to the room, there being an opening at the bottom of the grate for supply of air for combustion, an air conduit at the back of the grate whereby air passing therethrough is subject to influence of the heat of the said back wall of the grate, said back wall of the grate having means for supporting a heat absorbing element such as silica sand, means for discharging air through the passageway to thereby subject the same to heat by the heat absorbing means, said passageway having an opening at the top of the grate through which the air is discharged to the room, the upper end of the said backing member being shaped to cause gases of combustion to discharge into the air stream to temper the same prior to discharge into the room, and means for varying the volume of tempered air discharged into a room per unit of time.

5. Air conditioning means for rooms of a building separated by a partition wall comprising a pair of grates arranged in the partition wall, the back walls of the grates being in opposed and spaced relation providing a passageway therebetween, means for supplying heat to the front of the wall of each of the grates, means providing for a supply of air to the face of the grates, a transparent shield separating the faces of the grates from the interior of the respective rooms, means for supplying air to the passageway between the grates, there being an opening for discharge of air to the respective rooms at the top of each of the grates, the said upper end of the passageway being arranged to discharge the heated air from the face of the grate to the air stream prior to passing into the room.

6. Air conditioning means for rooms of a building separated by a partition wall comprising a pair of grates arranged in the partition wall, the back walls of the grates being in opposed and spaced relation, providing a passageway therebetween, means for supplying heat to the front of the wall of each of the grates, means providing for a supply of air to the face of the grates, a transparent shield separating the faces of the grates from the interior of the respective rooms, means for supplying air to the passageway between the grates, there being an opening for discharge of air to the respective rooms at the top of each of the grates, the said upper end of the passageway being arranged to discharge the heated air from the face of the grate to the air stream prior to passing into the room, a vertical conduit above the grates providing a continuation of the said passageway therebetween, and openings on each side of the said vertical conduit for discharging air to opposite sides of the partition.

7. Air conditioning means for rooms of a building separated by a partition wall comprising a pair of grates arranged in the partition wall, the back walls of the grates being in opposed and spaced relation, providing a passageway therebetween, means for supplying heat to the front of the wall of each of the grates, means providing for a supply of air to the face of the grates, a transparent shield separating the faces of the

grates from the interior of the respective rooms, means for supplying air to the passageway between the grates, there being an opening for discharge of air to the respective rooms at the top of each of the grates, the said upper end of the passageway being arranged to discharge the heated air from the face of the grate to the air stream prior to passing into the room, a vertical conduit above the grates providing a continuation of the said passageway therebetween, and openings on each side of the said vertical conduit for discharging air to opposite sides of the partition, and means for supplying moisture to the air stream prior to discharge into the respective rooms.

15

8. Air conditioning means for rooms of a building having a common partition wall comprising a pair of grate elements in said wall arranged in spaced relation back to back providing a passageway therebetween, said passageway being formed to provide discharge outlets at the top of the grate to the respective rooms on each of the opposite sides of the wall, a fuel burning element for each grate, means whereby gases of combustion produced by each fuel burning element discharges to the respective outlets of the passageway, and means for supplying air from atmosphere to the passageway.

EDWARD KENT.
